UNITED STATES PATENT OFFICE

SAMUEL A. MYERS AND JOHN J. KELLY, OF MEMPHIS, TENNESSEE.

COMBINED COTTON CHOPPER AND SCRAPER.

SPECIFICATION forming part of Letters Patent No. 299,248, dated May 27, 1884.

Application filed January 29, 1884. (No model.)

To all whom it may concern:

Be it known that we, SAMUEL A. MYERS and JOHN J. KELLY, of Memphis, in the county of Shelby and State of Tennessee, have invented a new and useful Improvement in Combined Cotton Choppers and Scrapers, of which the following is a full, clear, and exact description.

Reference is to be had to the accompanying drawings, forming a part of this specification, in which similar letters of reference indicate corresponding parts in all the figures.

Figure 1, Sheet 1, is a plan view of our improvement, part being broken away. Fig. 2, Sheet 2, is a sectional side elevation of the same. Fig. 3, Sheet 2, is a sectional rear elevation of a part of the same, taken through the broken line *x x x x x*, Fig. 2. Fig. 4, Sheet 2, is a sectional front elevation of a part of the same, taken through the line *y y*, Fig. 1.

20 The object of this invention is to facilitate the chopping of cotton-plants to a stand and the scraping of the rows of plants, and also to promote convenience in adjusting and controlling chopping and scraping machines.

25 The invention consists of the combination of parts and their construction, substantially as hereinafter described, and pointed out in the claims.

A is the frame of the machine, to the forward 30 end of which is attached the tongue B. The axle C of the wheels D is attached to the lower sides of the side bars of the frame A a little in the rear of their centers.

To the inner side of one of the wheels D is 35 secured a large beveled gear-wheel, E, into the teeth of which mesh the teeth of the small beveled gear-wheel F, attached to the rear end of a shaft, G. The rear end of the shaft G revolves in a bearing, H, placed in a slotted bracket, I, 40 attached to the side bar of the frame A. The bearing H is held outward by a spiral or other spring, J, placed between the said bearing and the inner end of the slot in the bracket I, the said spring being made of sufficient strength to 45 hold the gear-wheels E F in gear under ordinary circumstances. The spring J also allows the gear-wheels to be forced and held out of gear while the machine is traveling from place to place.

50 To the side of the small gear-wheel F are bolted one or two cams or sliding blocks K, which come in contact with segments L, attached

to an outwardly-projecting annular flange, M, formed around the gear-wheel E to receive them. When the cams K are detached from the gear-wheel F, the chopper hereinafter described will be swung back and forth at each revolution of the drive-wheel D as many times as the teeth of the gear-wheel E are multiples of the teeth of the gear-wheel F. When the 55 cams K are attached to the gear-wheel F, the said gear-wheel will be stopped as the cams K come in contact with the segments L, so that the revolution of the gear-wheel E will revolve the gear-wheel F a less number of times, and will 60 thus leave more plants in a hill. The forward part of the shaft G revolves in a bearing in a bracket, N, attached to the side bar of the frame A. To the forward end of the shaft G is attached a small crank, O, to which is pivoted the 65 end of a connecting-rod, P, the other end of which is pivoted to the chopper-standard Q at a little distance from the upper end of the said standard.

To the lower end of the standard Q is bolted 70 or otherwisecured the chopping-hoe R, which is made with a cutting-edge at each side, as shown in Fig. 3. The upper end of the chopper-standard Q is pivoted to the inner end 75 of a bar, S, the outer end of which is pivoted to the front cross-bar of the frame A.

Upon the forward side of the upper end of the chopper-standard Q, or of the bar S, is formed a boss or projection, T, to rest upon the upper side of the forward cross-bar of the 80 frame A and limit the downward movement of the said standard.

In the middle part of the bar S is formed a longitudinal slot to receive the pin of a small crank, U, attached to the end of a shaft, V, 85 which revolves in bearings formed in or attached to the forward cross-bars of the frame A.

To the rear end of the shaft V is attached a crank-arm, W, the outer end of which is widened to form a foot-rest, or has a foot-rest attached to it, so that the driver, by pressing the outer end of the crank-arm W downward with his foot, can raise the chopper-standard Q to raise the chopping-hoe R above the ground when desired.

To the inner sides of the rear parts of the side bars of the frame A are hinged, by bolts X, the upper ends of the scraper-standards Y.

To the lower ends of the standards Y are at-

tached rearwardly-projecting feet *Z*, to give steadiness of movement to the scrapers while at work. The forward sides of the lower ends of the standards *Y* are beveled to form seats 5 for the scrapers or sweeps *a*, and give the said scrapers a suitable inclination. The draft-strain upon the standards *Y* is sustained by the bars *b*, the forward ends of which are rigidly attached to the inner sides of the forward parts of the 10 side bars of the frame *A*. The rear parts of the bars *b* are slotted to receive the standards *Y*, so that the said bars will not interfere with the free upward movements of the said standards when being raised from the ground.

15 To the middle parts of the scraper-stands *Y* are attached the ends of a cross-bar, *c*, to the center of which is hinged, by an eyebolt or other suitable means, the rear end of a connecting-rod, *d*. The forward end of the rod *d* is hinged to the lower end of the lever *e*, which 20 is pivoted to a support attached to the middle cross-bar of the frame *A*. The upper end of the lever *e* projects into such a position that it can be conveniently reached and operated by 25 the driver from his seat to raise the scrapers from the ground when desired.

The driver's seat *f* is attached to the upper

end of the spring-standard *g*, the lower end of which is attached to the axle *C* or to the frame *A*.

Having thus described our invention, we 30 claim as new and desire to secure by Letters Patent—

1. In a combined cotton chopper and scraper, the combination, with the chopper-standard and the connecting-rod, of the shaft connected 35 by a crank to said rod, and having a pinion gearing with a cog or gear wheel on the driving-wheel, said pinion carrying a block sliding on smooth-faced segments disposed at intervals along the outer edge of the gear-wheel, 40 substantially as and for the purpose set forth.

2. In a combined cotton chopper and scraper, the combination, with the chopper-standard *Q* and the frame *A*, of the pivoted and slotted bar *S* and the shaft *V*, having crank-arms *U W*, 45 substantially as herein shown and described, whereby the chopper can be readily raised from the ground, as set forth.

SAMUEL A. MYERS.
